UNITED STATES PATENT OFFICE.

MARTHA B. HUSON, OF NEW YORK, N. Y.

STREET-CLEANING MACHINE.

1,026,445.

Specification of Letters Patent.

Patented May 14, 1912.

Application filed June 7, 1911. Serial No. 631,728.

To all whom it may concern:

Be it known that I, MARTHA B. HUSON, a citizen of the United States, and a resident of the city of New York, borough of Manhattan, in the county and State of New York, have invented a new and Improved Street-Cleaning Machine, of which the following is a full, clear, and exact description.

The object of the invention is to provide a new and improved street cleaner, arranged to insure a thorough cleaning of the pavement and gathering of the sweepings in the manner of hand-work, and to prevent dust from rising and scattering during the cleaning operation.

For the purpose mentioned, use is made of a receptacle for receiving the sweepings, and having its front bottom edge close to the pavement, and doors mounted to swing and to slide up and down on the front of the receptacle, the lower ends of the doors being provided with cleaning members adapted to project the sweepings into the receptacle during the inward swinging movement of the doors, the latter during the outward swinging motion being raised to lift the cleaning members off the pavement.

A practical embodiment of the invention is represented in the accompanying drawings forming a part of this specification, in which similar characters of reference indicate corresponding parts in all the views.

Figure 1 is a perspective view of the street cleaner showing the doors and cleaning members in operative position; Fig. 2 is a side elevation of the same, parts being shown in section and with the cleaning members in closed lowermost position; Fig. 3 is a similar view of the same showing the doors in raised and closed position; Fig. 4 is a longitudinal vertical section of the street cleaner showing the doors and cleaning members in raised and outermost position; Fig. 5 is a sectional plan view of the same on the line 5—5 of Fig. 4; and Fig. 6 is an enlarged perspective view of part of one of the doors and its cleaning member.

The receptacle A is mounted on or forms part of a vehicle B, preferably in the form

of a power truck or the like, the receptacle A projecting forwardly and having the front edge A' of its rearwardly and upwardly-inclined bottom A² normally close to the pavement, as plainly indicated in Fig. 5. The rear portion of the receptacle A is provided with an axle B carrying wheels C mounted to travel on the pavement so as to support the receptacle A in proper position. The front end of the receptacle A is open and is adapted to be closed by two doors D, D, having their lower ends in the form of cleaning members, of any approved construction; for instance, as shown in Fig. 1, the cleaning members E are in the form of squeegees, or in the form of bristles E', as indicated in Fig. 6. The doors D are each provided with a pintle D' mounted to turn and to slide vertically in bearings D² attached to the sides of the casing A, and springs F are coiled on the pintles D' and rest at their lower ends on lugs D³ attached to the doors D, the upper ends of the springs F abutting against the upper bearings D². The springs F serve to press the doors D downward, so that the members E engage the pavement with sufficient force to cause a proper sweeping of the pavement during the inward swinging movement of the doors and cleaning members. The doors D in swinging inward into a closed position are in lowermost position, and during the outward swinging movement the doors are in raised position, so that the members E are a desired distance above the pavement.

In order to raise and lower the doors, the following arrangement is made: On the pivoted edge of each door D is secured a supporting plate G, engaged at its under side by a friction roller H' journaled at one end of a lever H, fulcrumed at H² on the corresponding side of the casing A, and the rear end of the lever H is connected by a link H³ with a second lever H⁴ likewise fulcrumed at H⁵ on the side of the receptacle A, the rear end of the lever H⁴ carrying a friction roller H⁶ in engagement with the peripheral face of a cam I secured on the axle B. Now when the street cleaner is pushed forward over the pavement and the

wheels C are rotated, then the cams I impart an up and down swinging motion to the levers H⁴, which by the links H³ impart an up and down swinging motion to the 5 levers H, so that the friction rollers H' acting on the under side of the supporting plates G cause an up and down sliding of the doors D.

In order to impart a swinging motion to 10 the doors D in unison with the up and down movement given to the doors by the mechanism just described, use is made of links J pivotally connected with brackets J' attached to the inside of the doors D, and the 15 said links J are connected at their rear ends with a rod J² mounted to slide longitudinally in suitable bearings J³ attached to the under side of the top of the receptacle A, as plainly indicated in Fig. 4. The rod J 20 is pivotally connected by a link K with an arm L' fixed to a rock shaft L² journaled on the bottom A² of the receptacle A at the rear end thereof, the rock shaft having an arm L³ connected by a link N with a crank O 25 secured on the axle B. Now when the receptacle A is pushed forward, the wheels are rotated and then the crank O and link N impart a rocking motion to the rock shaft L² which by the link K imparts a longitudinal sliding motion to the rod J², so that 30 the links J impart a swinging motion to the doors D and their brushes E. As both the cams I and the crank O are mounted on the axle B, it is evident that both devices 35 manipulating the doors D are actuated in unison in such a manner that when the doors D swing into a closed position they are in a lowermost position, and after the doors are closed they are lifted into a raised 40 position and then swung outward while in this raised position, to be finally lowered into active position at the end of the outward movement. It is understood that during the inward or closing movement of the 45 doors D, the members E are in contact with the pavement so that the dirt and other matter are readily swept inward and over the edge A' of the bottom A² into the receptacle A, to accumulate therein. As the receptacle is continually moved forward, it is 50 evident that the doors D during their outward movement must be raised off the pavement so as not to disturb the dirt during the opening movement.

55 From the foregoing it will be seen that the dirt and other sweepings are swept into the receptacle A, and the front end thereof is closed for the time being, so that any dust arising during the sweeping operation is 60 not liable to rise in the air and scatter over surrounding property, but, on the contrary, is passed with the sweepings into the receptacle A to settle therein.

Having thus described my invention, I

claim as new and desire to secure by Letters 65 Patent:

1. A street cleaner, comprising a receptacle adapted to be pushed over the pavement and having an open front end, the front edge of the bottom of the receptacle 70 being close to the pavement, doors provided at their lower ends with cleaning members mounted to swing and to slide up and down on the sides of the receptacle at the front, and means for imparting a swinging motion 75 and an up and down motion to the said doors and cleaning members.

2. A street cleaner, comprising a receptacle adapted to be pushed over the pavement and open at the front, the front bottom edge of the receptacle being close to the ground, wheels on which the rear portion of the receptacle is supported, doors provided with cleaning members at their lower ends and mounted to swing and to slide up and 80 down on the sides of the receptacle at the front end thereof, cams turning with the said wheels, raising and lowering means controlled by the said cams and connected with the said doors to raise the doors and 85 cleaning members during the outward swinging motion, and to lower the doors and cleaning members to the pavement during the closing movement of the doors and cleaning members, and actuating means 90 controlled by one of the said wheels and connected with the said doors to swing the latter into open or closed position.

3. A street cleaner, comprising a wheeled receptacle open at the front, doors mounted 100 to swing and to slide up and down on the open front of the said receptacle, the lower ends of the doors being provided with cleaning members, means for imparting a swinging motion to the said doors, and means for 105 imparting an up and down motion to the said doors, both of said means having connection with the receptacle wheels, the doors during the closing movement being lowered, and raised during the outward movement. 110

4. A street cleaner, comprising a receptacle adapted to be pushed over the pavement and open at the front, the front bottom edge of the receptacle being close to the ground, wheels on which the rear portion of the receptacle is supported, bearings 115 on the sides of the receptacle at the front end thereof, doors having pintles mounted to turn and to slide up and down in the said bearings, cleaning members on the lower ends of the doors, supporting plates on the said doors, cams on the said wheels, lever mechanisms on each side of the receptacle and controlled by the said cams and engaging the said supporting plates to raise and lower the doors and cleaning members, links pivotally connected with the said doors and extending within the receptacle, a rod 120

125

mounted to slide in the receptacle and connected with the said links, a rock shaft mounted on the receptacle and provided with oppositely extending arms, a link connecting one of said arms with the said rod, and a crank and link connection between the other arm and one of the said wheels.

In testimony whereof I have signed my name to this specification in the presence of two subscribing witnesses.

MARTHA B. HUSON.
